[57] CLAIM

The ornamental design for a trivet, as shown and described.

DESCRIPTION

FIG. 1 is a perspective view of a trivet showing a first embodiment of my new design with a tray shown in phantom;

FIG. 2 is a top plan view thereof;

FIG. 3 is a side elevational view, the opposite side view being a mirror image thereof;

FIG. 4 is a bottom plan view thereof;

FIG. 5 is a front elevational view, the rear elevational view being a mirror image thereof;

FIG. 6 is a top plan view of a second embodiment of my new design;

FIG. 7 is a side elevational view, the opposite side elevational view being a mirror image thereof;

FIG. 8 is a bottom view thereof;

FIG. 9 is a front elevational view, the rear elevational view being a mirror image thereof;

FIG. 10 is a top plan view of a third embodiment of my new design;

FIG. 11 is a side elevational view, the opposite side elevational view being a mirror image thereof;

FIG. 12 is a bottom plan view thereof; and,

FIG. 13 is a front elevational view, the rear elevational view being a mirror image thereof.

The broken lines in FIG. 1 are for illustrative purposes only and form no part of the claimed design.
